UNITED STATES PATENT OFFICE.

SAMUEL S. SARGEANT, OF NEWARK, NEW JERSEY.

COMBINED BUCKLE AND SWIVEL.

SPECIFICATION forming part of Letters Patent No. 291,407, dated January 1, 1884.

Application filed October 31, 1883. (No model.)

To all whom it may concern:

Be it known that I, SAMUEL S. SARGEANT, of Newark, in the county of Essex and State of New Jersey, have invented an Improved 5 Combined Buckle and Swivel for Bridles; and I do hereby declare that the following is a full and exact description thereof, reference being had to the accompanying drawings, making part of this specification, in which—

10 Figure 1 is a front view of the combined buckle and swivel constructed with my improvements; Fig. 2, a side view of the same; Fig. 3, a central vertical section of the same as applied to a bridle; Fig. 4, a front view of a modified form of the buckle and swivel; Fig. 15 5, a side view of the same; and Fig. 6 is a central vertical section of the same applied to a bridle.

Like letters designate corresponding parts 20 in all of the figures.

The buckle proper, A, has an upper bar, *a*, middle pin-bar, *b*, with pin *c* thereon, and a lower bar, *d*. In addition to these bars, I add 25 a swivel-bar, *f*, between the pin-bar and lower bar, on which the swivel *B* is hung. This swivel-bar is of peculiar construction, substantially as shown. It has a downward-curved bend, *g*, in the middle, preferably equal to about a semicircle. On this downward curve 30 the eye *h* of the swivel is suspended, and its form allows the swivel to swing outward or inward, backward or forward, in any direction, with perfect freedom, adapting it to all the motions of the animal. As a special point 35 of improvement in the construction of this swivel-bar, I preferably form little projections *i* at the extremities of the curve on the upper side of the bar, to prevent the eye of the swivel from moving laterally out of the curve.

40 Instead of these projections, the curving might continue upward and form a complete eye.

With the construction of the buckle and swivel as above set forth, the throat-latch C, Fig. 3, of the bridle is secured to the pin-bar *b*, as shown, and in buckling, the billet D of the bridle crown-piece is passed under the upper part, *a*, of the buckle, over the pin-bar *b*, taking the pin *c* in one of the buckle-holes thereof, and then is passed under the lower

bar, *d*, of the buckle, thereby dispensing with 50 and saving a separate buckle on the throat-latch and leather loops on the same or another strap.

In Figs. 4, 5, and 6 I have shown a modification of the construction. In this modification I dispense with the lower bar of the buckle, as shown in Figs. 1, 2, and 3, and instead I use the swivel-bar *f* for a lower bar, and for that purpose raise it to the same plane or nearly the same height as the frame of the 60 buckle. In this case the crown strap or billet tucks under this swivel-bar, as shown in Fig. 6. This modification I prefer to use for adjusting up and down on the crown-billet D, as shown in the last-named figure, the pin *c* 65 entering any one of the buckle-holes of the billet to hold the buckle in place; and I make the throat-latch C, as usual, with buckles at both ends, so that the lower end of said billet, projecting beyond the swivel-buckle, buckles into the adjacent throat-latch buckle in the ordinary way. With this construction of the swivel-buckle, also, the throat-latch may be secured to the pin-bar *b*, but for that arrangement I prefer the construction first described. 75 With all these constructions and arrangements, however, the swivel *B* has the same freedom of motion in all directions, as above set forth.

Swivels have before been suspended by their pivots in notched bearings, but no capability 80 of swiveling in all directions is given thereby, as is the case with a swivel-eye suspended on a downwardly-curved bar.

What I claim as my invention is—

The combined buckle and swivel, constructed substantially as herein specified, the buckle being provided with a cross-bar, *f*, having a downwardly-curved part, *g*, and the swivel being provided with an eye, *h*, hung on the said curved part of the cross-bar, for 90 the purpose set forth.

In testimony whereof I have signed my name in presence of two witnesses.

SAMUEL S. SARGEANT.
